INCANDESCENT LAMP ASSEMBLY

Harry Ray Kiehl, Corning, N. Y., assignor to
Corning Glass Works, Corning, N. Y., a corpora-
tion of New York

Application April 17, 1943, Serial No. 483,424

4 Claims. (Cl. 176—32)

The present invention relates to an incandescent lamp assembly and has as its prime object maximum saving of metals required in the assembly.

To this end applicant has designed a lamp base for use in a socket of the Edison type, which requires but a small percentage of the metal ordinarily employed in a base of this character.

In the accompanying drawing

Fig. 1 is a plan view of a lamp assembly embodying the invention;

Fig. 2 is a side elevation of the same partly in section along line 2—2 of Fig. 1;

Fig. 3 is an enlarged plan view of the base portion only with a detail partly broken away; and

Fig. 4 is a fragmentary view showing alternative details of the assembly.

Referring to the drawing in detail, the lamp assembly comprises the usual sealed envelope 11, 20 having lead-in wires 12 and 13 projecting therefrom for connection with terminals adapted to make electrical contact with the shell and central contact button of an Edison type socket.

The base comprises a threaded shell 15 which may be conveniently molded of glass or other dielectric materials. The threads 16 are of the usual pitch adapted to thread into an Edison type socket. Transverse of threads 16 is a groove 17 for accommodating a terminal strip 18 and with an aperture 19 through which one end of the terminal strip 18 may be projected and bent over to anchor one end of the strip to the base. The surrounding space is then preferably luted with cement 22. An apertured boss 20 is also an integral part of base 15 and serves as a seat for an apertured disc 21 of conventional form usually employed as the central terminal of the assembly.

The interior of base 15 telescopes over and is attached to the base of envelope 11 with cement 22 with the wire 12 interposed between the envelope 11 and base 15 and its free end allowed to project exterior to base 15 opposite its groove 17. The terminal strip 18 at the end adjoining the envelope 11 has wire 12 attached thereto in any suitable manner, as by solder 23. The strip 18 is thus held against lateral movement by the groove 17 and is anchored at each end where it passes through and under shell 15. As is clearly apparent from Fig. 2, strip 18 is normally positioned intermediate the root and crest of threads 16 and will be pressed inwardly flush with the root of the threads by the lamp socket threads when the base is threaded into a lamp socket. Strip 55

18 is preferably made of phosphor bronze or some similar resilient metal and, accordingly, effects a very dependable electrical connection with the shell terminal of the lamp socket. The wire 13 is threaded through the apertures in boss 20 and disc 21 and solder is applied to anchor it in place.

In Fig. 4 the base is provided with a cavity 24 into which the upper end of a terminal strip 18' is projected and anchored with the aid of cement 10 22. This form of structure affords a further saving in metal employed and a reduction in cost of manufacture of the base. Preferably terminal strips 18 and 18' are given a slight curvature as shown in Figs. 1 and 3 to prevent unnecessary friction between the edges of the strip and the socket shell threads while the base is being threaded into or out of a socket.

From the foregoing it will at once be appreciated that the terminal strip 18 as used in place of the usually employed threaded metal shell effects a very material saving in metal without sacrifice of any of the dependable qualities of the metal shell form of structure.

Although in the foregoing there has been shown and described the preferred embodiment of the invention, it is to be understood that minor changes in details of construction may be resorted to without departing from the spirit and scope of the invention as claimed.

30 I claim:

1. In an incandescent lamp assembly, an envelope, a lamp base attached to said envelope composed of a threaded shell of dielectric material, and a strip of resilient conductive material extending transverse to the shell threads and electrically connected to a conducting element within said envelope.

2. In an incandescent electric lamp, a lamp envelope, a base of dielectric material having 40 threads formed on the exterior thereof for threading into a light socket, and a narrow band of metal arranged adjacent to but transverse of the threads for establishing electrical connections between the interior of the envelope and the shell 45 terminal of a lamp socket into which the base is adapted to be threaded.

3. In a lamp assembly, a sealed envelope having protruding wires for conducting electrical current into the interior of the envelope, a glass base attached to the end of the envelope from which the wires protrude; said base having surrounding threads for threading the same into an Edison type electric lamp socket, said base having a channel transverse of its threads for accommodating a metal terminal for contact with the shell

of a socket and having an aperture for accommodating a button for electrical contact with the socket base, a metal terminal in said channel having one end attached to one of the protruding wires, and a conducting button arranged over the base aperture and attached to the other of the protruding conducting wires.

4. As an article of manufacture, an incandescent lamp comprising a base composed of a rigid dielectric material having a threaded outer surface adapted to be threaded into a lamp socket,

5 said base having a longitudinal groove running transverse of said threads and of greater depth than the root diameter thereof, a resilient electrical conductor connected to said base at either end of said groove and normally occupying a position in said groove intermediate the root and the crest of said thread, said conductor being displaceable into said groove flush with the root of said thread when the base is screwed into a lamp socket.

10 HARRY RAY KIEHL.
